UNITED STATES PATENT OFFICE.

OTTIS K. BROWN, OF NEWPORT NEWS, VIRGINIA, ASSIGNOR TO PYRAMID BEVERAGES, INCORPORATED, OF NEWPORT NEWS, VIRGINIA, A CORPORATION OF VIRGINIA.

DESIGN FOR A BOTTLE.

Application filed May 16, 1929. Serial No. 31,259. Term of patent 14 years.

To all whom it may concern:

Be it known that I, OTTIS K. BROWN, a citizen of the United States, residing at 3311-3313 Huntington Ave., city of Newport News, in the county of Warwick and State of Virginia, have invented a new, original, and ornamental Design for Bottles, of which the following is a specification, reference being had to the accompanying drawing, forming part thereof.

The figure is a side view in elevation of a bottle, showing my new design. The alternate side view in elevation of the bottle is identical with the design shown.

I claim:

The ornamental design for a bottle, as shown and described.

OTTIS K. BROWN.
